UNITED STATES PATENT OFFICE

2,620,557

CAN OPENING AND SPOUT FORMING DEVICE

John F. Walters, Battle Creek, and Edward C. Fisher, Mattawan, Mich.

Application November 13, 1951, Serial No. 255,952

8 Claims. (Cl. 30—63)

1

The present invention relates broadly to can opening devices, and in its specific phases to a spout forming can opener.

Many forms of can openers have been proposed in the past, and a few of them have included spout forming members. The can openers of the latter type have had one or more definite limitations such as not being adaptable for use on different size cans, operating only on flanged end cans when condensed milk cans commonly do not have flanged ends, or require tilting pressure on the can opener handle to form a spout with the inherent danger of tipping the can and spilling part or all of its contents. It was a recognition of these difficulties and shortcomings of the prior art, and the need of a simplified spout forming can opener which lead to the conception and development of the present invention.

Accordingly among the objects of the present invention is the provision of a spout forming type of can opener which operates on all sizes of cans, does not require the can to have a flanged end, and wherein no tilting action is required for the formation of the spout.

Another object of the present invention is to provide a spout forming type of can opener which is easy to manufacture, is of low cost, positive in action, and easy to use.

A further object is to provide a can opener having a piercer with a pair of spaced apart guide members adapted to contact the outer face of the can at opposite sides of the point in the top of the can where the piercing takes place so that the piercer is guided during its piercing movement.

A further object is to provide a pivoted and hook-ended handle member with its hook end nesting in the piercing portion of the can opener and adapted to pass therewith into the can, and then upon squeezing the handle portion of the hook-ended member toward the handle shaped frame portion carrying said piercer and pivot, said hook end will move outward and form a spout between the guide members projecting from the frame portion and in contact with the outer face of the can to be opened.

A further object is to provide a spout forming type of can opener with a pusher mounted on the frame thereof directly adjacent the piercer, guide members, and hook end of a spout forming handle member to promote stability of the device during the piercing operation and to permit the piercer and guide members, when in spout forming position, to hold the can and minimize danger of tipping it over during the spout forming operation.

2

A further object is to make a spout forming type of can opener wherein the hook-ended spout forming member is readily removable for ease of washing and drying the complete assembly.

Still further objects and advantages of the invention will appear as the description proceeds.

To the accomplishment of the foregoing and related ends, the invention, then, consists of the can opening and spout forming means herein-after fully described and particularly pointed out in the claims, the annexed drawing and the following description setting forth in detail certain means for carrying out the invention, such disclosed means illustrating, however, but one of various ways in which the principle of the invention may be used.

In the annexed drawing:

Figure 1 shows a side view of the can opening and spout forming device of the present invention in position ready for use.

Figure 2 shows an end view of the device of the present invention as seen from the left hand end of Figure 1.

Figure 3 shows a bottom view of the device illustrated in Figure 1.

Figure 4 shows an enlarged substantially center longitudinal section view of the head portion of the can opening and spout forming device after the piercing member of same has been forced into the can and before forming a spout therein.

Figure 5 is a view similar to Figure 4 and with the hook-ended handle member pivotally moved to spout forming position.

Referring more particularly to the drawing, it will be noted that the can opener assembly 1 has a frame portion 2 particularly adapted to be made as a forging or by stamping from a single piece of suitable sheet metal. Where sheet metal is used, the same is preferably formed to produce a handle 3 with downturned reinforcing flanges 4 and 5 at each side. At the end of those reinforcing flanges they are preferably provided with depending guide members 6 and 7 having notches 8 and 9 in their forward edge to provide clearance under conditions of use of the device. These guide members 6 and 1 are also preferably provided with ears 10 and 11 which are adapted to be bent inward toward each other as is more particularly shown in Figures 2 and 3 to provide support for the piercing member 12, and to which they can be spot welded or otherwise fastened if desired. This piercing member may be in the form of a turned-down end portion of frame 2 with the point 13 of same sharpened and of a generally V shape. The piercing member 12 is

50
55

preferably provided with a rib 24 as shown, not only for strength but also for another purpose to be later described.

Mounted on the upper edge of frame 2 above guide members 6 and 7 is a knob 14 which can be fastened in place in any convenient manner such as by means of a screw 15 extending through a perforation 16 in frame 2 as is more particularly shown in Figures 4 and 5. This knob 14 being above the piercing member and close to same provides an ideal and simplified member adapted for pushing to force the point 13 of piercing member 12 into the can 25 while its movement is guided by means of guide members 6 and 7.

In order to form the spout, there is provided a movable handle member 17 mounted on a pivot member 18 of any suitable type such as a cotter pin. Frame 2 would be suitably perforated at opposite sides in alignment for such pivot member so that the handle can be pivotally mounted substantially in the position shown. Movable handle member 17 is also provided with a head member 19 having a depending hook end adapted to fit into the rib 24 in piercing member 12 so that the point of such hook will follow the piercing member into the can during the piercing operation. The movable handle member is also provided with a perforation 20 adapted to fit pivot member 18 as is more particularly illustrated in Figures 4 and 5.

In order to hold the edge of head member 19 normally in the recess of piercing member 12, a compression spring 21, which may be of any convenient form, such as a coil spring as shown, is mounted on movable handle member 17 at a prescribed location which for instance may be determined by means of a notch 22 in which the spring may be anchored by peining or in any other convenient manner. Under these conditions if movable handle member 17 is removed the spring will go with it, a thing which will facilitate washing and sterilizing the whole apparatus. In order to stabilize the upper end of spring 21 under conditions of use, frame 2 may have a tab member 23 formed therein and bent downward as shown in Figures 4 and 5. This same tab member 23 may also act as a stop member relative to the spout forming movement of movable handle member 17, as is more particularly shown in Figure 5.

To use the device, it is placed over the top edge of the can 25 with guide members 6 and 7 contacting the outer face of the can as shown in Figure 1. By holding the device substantially horizontal and pushing down on knob 14 the piercing point 13 of piercing member 12 will be forced down into the can until the upper end of notches 8 and 9 of guide members 6 and 7 will come in contact with the top of the can. Such procedure carries the hook-shaped point of head member 19 of the movable handle member 17 into the top of the can as is shown in Figure 4. Then by pivotally moving movable handle member 17 toward frame member 2, in the manner of a pair of pliers or shears, head member 19 will pivot about pivot member 18 to the position shown in Figure 5. During this movement guide members 6 and 7 bear against the outer face of the can and support same during the formation of the spout between them, and in doing so they limit the width of the spout and provide the holding power necessary to resist any tendency of the can to move and prevent the spout formation. With the spout formed, the can opening

and spout forming device is then ready to be removed and washed or rinsed to prepare same for the next time it is to be used.

This device can be made from ordinary mild steel or even a better steel if desired. However, mild steel is relatively easy to work and the point 13 of piercing member 12 will hold its edge for a long period of time without any special treatment. However, if a higher grade of steel is used same can be heat treated to harden and lengthen the life of the point 13, or if mild steel is used and its piercing powers are to be increased, the piercing point can be case hardened by the familiar cyanide process or even by the pack hardening carbonization process, coupled of course, in each instance, with appropriate heat treatment to provide the necessary hardness.

Other modes of applying the principle of our invention may be employed instead of those explained, change being made as regards the apparatus herein disclosed, provided the means stated by any of the following claims or the equivalent of such stated means be employed.

We therefore particularly point out and distinctly claim as our invention:

1. A can opening and spout forming device, comprising a frame member which is in the form of a handle having a pair of spaced apart guide members projecting sidewise from said handle and adapted to contact the outer side face of a can to be opened, a piercing member substantially between said guide members and adapted to be forced into the end of said can, and means pivotally mounted on said frame member between said guide members for use with same to form a spout in said can between said guide members.

2. A can opening and spout forming device as set forth in claim 1, wherein said pivotally mounted means has a head member with point extending along the piercing member, said point being adapted to pass into the top of said can with said piercing member when the latter is forced thereinto in position for forming said spout.

3. A can opening and spout forming device as set forth in claim 1, wherein there is a pivot member extending crosswise of said frame adjacent said piercing member and between said side-projecting guide members, said pivotally mounted means being mounted on said pivot member, said pivotally mounted means having a head member with a point extending along said piercing member and adapted to pass into the top of said can with said piercing member when the latter is forced thereinto in position for forming said spout, said pivotally mounted means having an operating handle extending from said head member in position such that when same is moved toward said handle portion of said frame, the point of said head member will move away from said piercing member and bend the edge of the end of said can outward between said guide members to form a spout.

4. A can opening and spout forming device as set forth in claim 1, wherein said piercing member has an outwardly extending rib, and said pivotally mounted means for forming the spout has a head member extending into said rib, said head member having a point adapted to pass into the top of said can with said piercing member when the latter is forced thereinto in position for forming said spout.

5. A can opening and spout forming device, which comprises a frame member which is in the form of a handle having at one end thereof a pair

of spaced-apart guide members projecting side-
wise from and on the same side of said handle
and having a knob at the opposite side of said
frame and adjacent said guide members, said
guide members being adapted to contact the
outer side face of a can to be opened, a piercing
member substantially between said guide mem-
bers and adapted to be forced into the end of
said can, and means pivotally mounted on said
frame member between said guide members for
use with same to form a spout in said can between
said guide members.

6. A can opening and spout forming device as
set forth in claim 5, wherein said piercing mem-
ber has an outwardly extending rib extending
lengthwise thereof, and said pivotally mounted
means for forming said spout has a head mem-
ber extending into said rib, said head member
having a point between said guide members and
adapted to pass into the top of said can with said
piercing member when the latter is forced there-
into in position for forming said spout.

7. A can opening and spout forming device as
set forth in claim 5, wherein there is a pivot
member extending crosswise of said frame adjac-
ent said piercing member and between said side-
wise projecting guide members but adjacent the
frame portion from which they extend, said pivot-
ally mounted means being mounted on said
pivot member, said pivotally mounted means
having a head member with a point extending
along said piercing end thereof with said point
adapted to pass into the top of said can with said
piercing member when the latter is forced there-
into in position for forming said spout, said

pivotal means having an operating
handle extending from said head member in posi-
tion such that when same is pivotally moved to-
ward said handle portion of said frame, the point
of said head member will move away from said
piercing member and bend the edge of said can
outward between said guide members to form a
spout.

8. A can opening and spout forming device as
set forth in claim 5, wherein said piercing mem-
ber has an outwardly extending rib extending
lengthwise thereof, a pivot member extending
crosswise of said frame adjacent said piercing
member and between said sidewise projecting
guide members but adjacent the frame portion
from which they extend, said pivotally mounted
means being mounted on said pivot member, said
pivotally mounted means having a head member
extending into said rib, said head member hav-
ing a point between said guide members and
adapted to pass into the top of said can with said
piercing member when the latter is forced there-
into in position for forming said spout, said pivot-
ally mounted means having an operating han-
dle extending from said head member in position
such that when same is moved toward said handle
portion of said frame, the point of said head
member will move out of said groove in said
piercing member and engage and bend the edge
of the end of said can outward between said guide
members to form a spout.
